UNITED STATES PATENT OFFICE.

WILLIAM C. HUSS, OF CINCINNATI, OHIO.

DESIGN FOR A KITCHEN-CABINET.

48,493.

Specification for Design.

Patented Feb. 1, 1916.

Application filed August 11, 1915. Serial No. 45,049. Term of patent 7 years.

To all whom it may concern:

Be it known that I, WILLIAM C. HUSS, a citizen of the United States, residing at Cincinnati, in the county of Hamilton and State of Ohio, have invented a new, original, and ornamental Design for a Kitchen-Cabinet, of which the following is a specification, reference being had to the accompanying drawing, forming part thereof.

The figure is a perspective view of a kitchen cabinet showing my new design.

I claim:

The ornamental design of a kitchen cabinet, as shown.

WILLIAM C. HUSS.

Witnesses:

WALTER F. MURRAY,
W. THORNTON BOGERT.
